UNITED STATES PATENT OFFICE.

ROBERT W. SCOTT, OF LEEDS POINT, NEW JERSEY, ASSIGNOR OF ONE-HALF TO LOUIS N. D. WILLIAMS, OF OGONTZ, PENNSYLVANIA.

KNITTED FABRIC.

No. 885,794

Specification of Letters Patent.

Patented April 28, 1908.

Application filed June 6, 1907. Serial No. 377,604.

To all whom it may concern:

Be it known that I, ROBERT W. SCOTT, a citizen of the United States, residing in Leeds Point, Atlantic county, New Jersey, have invented certain Improvements in Knitted Fabrics, of which the following is a specification.

My invention relates to that class of knitted webs, either ribbed or plain, or partly ribbed and partly plain, which have certain wales discontinued, or have wales of one face discontinued and supplanted by wales of the other face, the object of my invention being to prevent "running-back" of the terminal stitches of the discontinued wales.

In the accompanying drawings—Figure 1 is an exaggerated view of a piece of fabric partly ribbed and partly plain, having discontinued rib wales whose terminal stitches are prevented from running back by being treated in accordance with my invention; Fig. 2 is a similar view illustrating another method of carrying out my invention; Fig. 3 is an exaggerated view of a piece of knitted web, partly ribbed and partly plain, and having the discontinued rib wales supplanted by plain wales; the running-back of the terminal stitches of the discontinued wales being prevented by means similar to those shown in Fig. 1, and Fig. 4 is a view similar to Fig. 3 but showing the running-back of the terminal stitches of the discontinued wales prevented by means similar to those shown in Fig. 2.

Although my invention is applicable to plain webs, to ribbed webs, or to webs which are partly ribbed and partly plain, I have selected the latter type of web for illustrating my invention, *a* representing the standing wales which are continued throughout both the ribbed and the plain portions of the web, and *b* representing the rib wales which are discontinued at the point where the character of the web changes from ribbed to plain.

In the web shown in Fig. 1, the terminal stitch *x* of each of the discontinued rib wales is carried across the adjoining plain wale and engaged thereby, but it forms no part of the permanent structure of said wale, its retention being due to frictional hold upon it and not to an actual interlooping of a stitch of the retaining wale with said terminal stitch. The same is true of the web shown in Fig. 2, although in this case the terminal stitch *x*,

instead of being engaged with the adjoining standing wale by being laid across the same as in Fig. 1, is drawn through a stitch of said standing wale.

In order to permit of its proper disposal in either of the ways described the terminal stitch *x* is longer than the stitches in the adjacent portions of the web, and this added length, coupled with the frictional hold of the standing wale upon said terminal stitch, prevents the pulling of the same through the preceding stitch of the discontinued wale by reason of any strain likely to be exerted upon the web.

The webs shown in Figs. 3 and 4 are similar to the webs shown in Figs. 1 and 2, respectively, with the exception that plain wales *d* supplant the discontinued rib wales, and, in the event of the discontinued wales being plain wales, rib wales may supplant the latter in the same manner.

In order to effect the disposal of the terminal stitches *x* in the manner shown in Figs. 1 and 3, the dial needles may be shogged laterally after having drawn their elongated terminal stitches so as to lay the latter stitches in front of the adjoining plain web needles and behind the latches of the same, whereby they will be cast from said plain web needles together with the stitches already upon the latter when the succeeding stitches are drawn by said needles, the terminal loops being then cast from the dial needles and the latter retired from action. In effecting the disposal of the terminal stitches in the manner shown in Figs. 2 and 4 the dial needles are shogged in the same manner but the terminal stitches *x*, instead of being laid behind the latches of the plain web needles, are laid in the hooks of the same, so that when said needles cast their stitches the terminal stitches will be drawn through said stitches together with the new stitches which are being drawn.

In producing the web shown in Figs. 3 and 4 plain web needles are brought into action upon or after the retirement of the ribbing needles, and, in this case, the disposal of the terminal stitches of the discontinued rib wales in the manner described has the effect of closing, in some measure, the eyelet holes which would otherwise be produced by the initial loops of the supplanting wales.

In applying my invention to ribbed webs other than the one-and-one web which I have selected for illustration, the discontinuance

of some of the wales, whether or not the same are supplanted by wales of the other face, may simply be for the purpose of changing the character of the rib, the web preserving a ribbed form throughout.

5 5. I claim:—

1. A knitted web having discontinued wales whose terminal stitches are engaged with adjoining wales but do not form part of the permanent structure of such wales.

10 2. A knitted web having discontinued wales whose terminal stitches are drawn through the stitches of adjoining wales.

15 3. A knitted web having discontinued rib wales whose terminal stitches are engaged with adjoining wales but do not form part of the permanent structure thereof.

20 4. A knitted web, partly ribbed and partly plain, having discontinued rib wales whose terminal stitches are engaged with adjoining wales but do not form part of the permanent structure thereof.

25 5. A knitted web having discontinued rib wales whose terminal stitches are drawn through stitches of adjoining wales.

6. A knitted web, partly ribbed and partly plain, having discontinued rib wales whose terminal stitches are drawn through stitches of adjoining wales.

30 7. A knitted web having wales of one face discontinued and supplanted by wales of the other face, the terminal stitches of said discontinued wales being engaged with adjoining wales but forming no part of the permanent structure of such wales.

35 8. A knitted web, partly ribbed and partly plain, having wales of one face discontinued and supplanted by wales of the other face, the terminal stitches of said discontinued wales being engaged with adjoining wales but forming no part of the permanent structure of such wales.

40

9. A knitted web having wales of one face discontinued and supplanted by wales of the other face, the terminal stitches of said discontinued wales being drawn through stitches of adjoining wales.

10. A knitted web, partly ribbed and partly plain, having wales of one face discontinued and supplanted by wales of the other face, the terminal stitches of said discontinued wales being drawn through stitches of adjoining wales.

11. A knitted web having discontinued rib wales supplanted by corresponding plain web wales and having the terminal stitches of said discontinued wales engaged with adjoining wales but forming no part of the permanent structure thereof.

12. A knitted web, partly ribbed and partly plain, having discontinued rib wales supplanted by corresponding plain web wales and having the terminal stitches of said discontinued wales engaged with adjoining wales but forming no part of the permanent structure thereof.

13. A knitted web having discontinued rib wales supplanted by corresponding plain wales but having terminal stitches of said discontinued rib wales drawn through stitches of adjoining wales.

14. A knitted web, partly ribbed and partly plain, having discontinued rib wales supplanted by corresponding plain web wales but having terminal stitches of said discontinued rib wales drawn through stitches of adjoining wales.

In testimony whereof, I have signed my name to this specification, in the presence of two subscribing witnesses.

ROBERT W. SCOTT.
